UNITED STATES PATENT OFFICE.

DOROTHY W. LITTLEFIELD, OF SPRINGVILLE, NEW YORK.

DESIGN FOR A DOLL.

Application filed January 12, 1922. Serial No. 169. Term of patent 3½ years.

To all whom it may concern:

Be it known that I, DOROTHY W. LITTLEFIELD, a citizen of the United States, residing at Springville, in the county of Erie and State of New York, have invented a new, original, and ornamental Design for Dolls, of which the following is a specification, reference being had to the accompanying drawings, forming part thereof, wherein—

I claim:

The ornamental design for a doll, as shown.

In testimony whereof, I affix my signature.
DOROTHY W. LITTLEFIELD.
